TROUSERS RECTIFIER

Harry H. Stiebel, Brooklyn, N. Y.

Application October 30, 1939, Serial No. 301,928

5 Claims. (Cl. 2—233)

This invention relates to devices supported on the legs for rectifying the deformation of trousers when worn by bow-legged men. Many devices for this purpose have been proposed but up to now none has been generally satisfactory because of one or more failures to meet all the conditions of use.

Among the objects of this invention are: To provide a device that holds its fixed position on the leg firmly and securely; that is so constructed that it is practically unbreakable in use; that is stream-lined, air-conditioned, and perspiration-proof; that provides a support for the hose; that in one form provides a positive lock against displacement; that is easily attached and detached; and the elastic portions of which including the hose supporters are manually replaceable. Other objects will appear as the description proceeds.

Reference is made to the drawing in which:

Figure 1 is a plan view showing the intersected section of a trousers leg in outline, taken below the knee.

Figure 2 is a side perspective view.

Figure 3 is a section on the line 3—3 of Figure 2.

Figure 4 is a side view of a modification.

Figure 5 is a front view of a modification.

A trouser leg 10 as shown in Figure 1 hangs in the normal position in engagement on the inside of the leg with my improved rectifier 11 secured on the leg (not shown). The rectifier 11 is formed as a wide flat band of rigid material in the form of a crescent, the outer part of the crescent presenting a wide convex section of a cylinder engageable at the central portion with the inside of the trousers to prevent inward bulging or bowing of the cloth on a bow leg; the inner part 12 of the crescent has a curvature that conforms with the inside contour of a bow leg below the knee and above the calf; a preferred material for the crescent is flat plastic material about one inch wide and formed in an integral or unitary crescent. In manufacture a plurality of sizes may be made for ready fitting to different legs, being made in similar pairs. The width of the material of the crescent is such that when the inner part 12 tightly fits the leg the crescent is held in the horizontal position. An elastic band 13 may have at the ends the usual fasteners 14 and an adjusting buckle 15 and be of sufficient width to cover the inner wall of the inner part 12 of the crescent 11. Attaching members 16 and 17 are secured preferably by stitching to the outer wall of the band 13 at such positions that when their free ends are overlapped on the inner parts 12 of the crescent 11 they engage the inside of the

crescent at the ends and prevent movement of the crescent in both directions around the leg so that it is held positively in the adjusted position inside the leg. The free ends of the members 16 and 17 are adapted to fold over each other and may be locked together by any suitable means such as a button or stud and socket fastener 18. A reinforcing piece 19 may be stitched to the outside of the band 13 and secured underneath the attaching members 16 and 17 and centrally from the lower edge may depend the elastic strap 21 of any well known hose supporter 22 usually provided with an adjusting buckle 23 for varying the length for adjustment.

15 A modification is shown in Figures 4 and 5 in which the hose-supporter strap 21, instead of depending from the band 13, is suspended by looping the upper end thru a slot 24 formed centrally in the outer part of the crescent 11. The buckle 23 is adjusted so that the hose supporter 22 exactly engages the top of a hose 25. A second strap 26, preferably elastic, is also secured in the slot 24 and extends upwardly to a belt 27, adapted to extend around the waist, to which it is secured centrally at the front. A buckle 28 provides for adjustment of the strap 26 to exactly counterbalance the strap 21 and to positively hold the crescent 12 in the horizontal position. In addition the strap 26 prevents the upper part 20 of the trousers from bowing in against the inside of or towards the thigh. The other strap 26 from the rectifier on the other leg also is attached at the front center of the belt 27, which 25 may have a locking and adjusting buckle 28, of well known construction.

Having disclosed two forms of my invention and realizing that, in view of my disclosure, many changes, omissions, and substitutions will readily occur to those skilled in the art, but within the spirit and scope of my invention, I do not limit myself to the exact forms shown.

I claim:

1. A trousers rectifier for bowlegged men comprising in combination a rigid crescent-shaped member formed of flat material of sufficient width to maintain a flat position against the leg and to flatly engage the inside of the trousers for a sufficient area to prevent bulging, the curvature of the inner part of the crescent substantially conforming to the inner contour of the leg above the calf and below the knee, the curvature of the outer part of the crescent conforming centrally to the normal curvature of the trousers, and a flat band attached to and covering the inner wall 45 of the crescent 11.

of the crescent and adapted to grip the leg elastically.

2. A trousers rectifier for bow-legged men comprising in combination a rigid crescent-shaped member formed of flat material of sufficient width to maintain a flat position against the leg and to flatly engage the inside of the trousers for a sufficient area to prevent inward bowing, the curvature of the inner part of the crescent substantially conforming to the inner contour of the leg above the calf and below the knee, the curvature of the outer part of the crescent conforming centrally to the normal curvature of the trousers, a flat band covering the inner wall of the crescent and adapted to grip the leg elastically, and means for attaching the band to the inner wall of the crescent at each end comprising two ends of attaching tape and a clasp for securing the ends together so that the band is quickly attached and detached and the crescent is secured against slipping with reference to the band.

3. A trousers rectifier for bow-legged men comprising in combination a rigid crescent-shaped member formed of flat material of sufficient width to maintain a flat position against the leg and to flatly engage the inside of the trousers for a sufficient area to prevent inward bowing, the curvature of the inner part of the crescent substantially conforming to the inner contour of the leg above the calf and below the knee, the curvature of the outer part of the crescent conforming centrally to the normal curvature of the trousers, a flat band adapted to grip the leg elastically, means for attaching the band to the inner part of the crescent, and a hose supporter suspended therefrom.

4. A trousers rectifier for bow-legged men comprising in combination a rigid crescent-shaped member formed of flat material of sufficient width

to maintain a flat position against the leg and to flatly engage the inside of the trousers for a sufficient area to prevent inward bowing, the curvature of the inner part of the crescent substantially conforming to the inner contour of the leg above the calf and below the knee, the curvature of the outer part of the crescent conforming centrally to the normal curvature of the trousers, a flat band adapted to grip the leg elastically, two spaced apart members attached to the flat band and engaging the inner ends of the crescent to hold it against circumferential slipping with reference to the band, and manually operable means for attaching the ends of each member together over the inside of the crescent.

5. A trousers rectifier for bow-legged men comprising in combination a rigid crescent-shaped member formed of flat material of sufficient width to maintain a flat position against the leg and to engage the inside of the trousers for a sufficient area to prevent inward bowing, the curvature of the inner part of the crescent substantially conforming to the inner contour of the leg above the calf and below the knee, the curvature of the outer part of the crescent conforming centrally to the normal curvature of the trousers, a flat band adapted to grip the leg elastically, means for attaching the band to the inner part of the crescent, a hose-supporting strap centrally attached to the outer part of the crescent and extending downwardly, a strap also attached centrally to the outer part of the crescent and extending upwardly, and means for suspending said last-named strap from the waist, so that the crescent member is secured positively in a horizontal position and the upper part of the inside of a trousers leg is held against inward bowing.

HARRY H. STIEFEL.
